GOGGLES

James W. Welsh, Providence, R. I., assignor to
Welsh Manufacturing Company, a corporation
of Rhode Island

Application February 15, 1938, Serial No. 190,546

1 Claim. (Cl. 2—14)

This invention relates to a goggle; and has for one of its objects to provide a goggle which may be worn for diving or swimming under water to exclude the water from the eyes that the eyes may be opened under water without the discomfort sometimes attendant upon the water entering the eyes.

Another object of the invention is to provide a goggle which may be used in certain occupations where smoke or gases are circulating that may cause discomfort to the eyes.

A further object of the invention is to provide in such a goggle a structure which will seal the eyes against the entrance of gases or water even though there be irregularities of the face about the eyes.

Another object of the invention is to provide a simple structure with transparent portions which are firmly held in position and yet which may be readily removed and replaced should they become scratched or damaged.

With these and other objects in view, the invention consists of certain novel features of construction, as will be more fully described, and particularly pointed out in the appended claim.

In the accompanying drawing:

Fig. 1 is a face view of the front portion of the goggle;

Fig. 2 is a rear view of the front body portion of the goggle;

Fig. 3 is a sectional view on line 3—3 of Fig. 2;

Fig. 4 is a sectional view substantially at right angles to the section of Fig. 3;

Fig. 5 is a sectional detail of the claspings part of the goggle for securing the head encircling strap.

In some occupations where smoke or gases occur or in swimming under water or diving, it is often desirable to have some shield for the eyes to prevent the discomforts of gases or salt water entering the eyes and yet permit the user of the goggles to see; and in order that this may be accomplished, I have provided a goggle with ribs or molded formations which will engage the face about the eyes to tightly seal the chambers which contain the transparencies for the eyes from the entry of gases or water, thus effectively accommodating the goggle to the contour of the face about the eyes for effecting this seal; and the following is a more detailed description of the present embodiment of this invention, illustrating the preferred means by which these advantageous results may be accomplished.

With reference to the drawing, 10 designates the body portion of the goggles preferably formed

of some moldable elastic material such as rubber or "Duprene", with reduced ends 11 to which ends there is suitably attached, a strap 12 for encircling the head and holding the body portion 10 tightly against the face.

Chambers 14 are provided at the location of each of the eyes by molding the material so as to provide outwardly extending walls 15 with inwardly extending flanges 16 having recesses 17 therein for the reception of windows 18 which may be formed of some transparent material such as glass or Celluloid but are preferably formed of Celluloid. The outer edge 19 of the flange is sufficiently flexible and resilient so that the windows 18 may be positioned by reason of the elasticity of the flange, but when in place will so expand the flange as to form a tight connection that there may be no entry of water or gases through the connection to enter the chambers above mentioned.

There is also molded on the body portion 10 a series of ribs 20, 21 and 22. These ribs are generally concentrically arranged but the rib 21 merges into the rib 22, while there is an additional rib 23 merging into the rib 22. These ribs are of different thicknesses and contours so as to fit the usual formation of the face about the eyes; and by reason of their resiliency and the elasticity of the rubber forming the body and ribs will conform somewhat to the shape of the face and firmly press against all parts of the face circularly about the eyes so as to tightly seal the eyes against the entrance of gases or water. The bridge portion 25 connecting the two chambers also has a rib 26 extending along it to join the ribs 22 but by reason of the concentric ribs 22 encircling the eyes it is non-essential that there be a rib 26 to prevent water passing between the bridge 25 and the face. This rib 26, however, may serve to break the force of any water which might tend to circulate therethrough.

In order to attach the strap 12 to the reduced ends 11 of the body the stud portion 28 of a snap fastener is mounted in each end portion 11 while at each end of the strap a buckle 29 carrying a mating socket portion 30 of the snap fastener is adjustably mounted on the end 31 of the strap 12 for detachable engagement with the studs of the snap fastener 28 as desired. In this manner the elastic strap 11 may be adjusted for the encircling of heads of different sizes.

The foregoing description is directed solely towards the construction illustrated, but I desire it to be understood that I reserve the privilege of resorting to all the mechanical changes to which

the device is susceptible, the invention being defined and limited only by the terms of the appended claim.

I claim:

5. In a goggle having water tight eye cups, a flexible body portion for engaging the face about the eyes having eye cups with sight transparencies at the eyes, and a generally smooth inner surface, a plurality of spaced resilient ribs ex-

tending rearwardly from the inner surface of said body and completely about each eye cup, the outer of said ribs about each cup being of a greater depth or thickness than the inner rib and greater than any other portion along its extent 5 at the location of the hollow of the face under the eye to extend into such hollow or recess of the face.

JAMES W. WELSH.
